UNITED STATES PATENT OFFICE

JAMES COLEY, OF LEICESTER, ENGLAND, ASSIGNOR TO WILDT AND COMPANY LIMITED,
OF LEICESTER, ENGLAND, A BRITISH COMPANY

YARN-WINDING MACHINE

Application filed June 29, 1929, Serial No. 374,758, and in Great Britain March 28, 1929.

This invention consists in improvements in or relating to yarn-winding machines wherein the feed of the riser is effected partly by mechanical means and partly by frictional contact of the riser with the wound yarn. The type of riser mechanism to which the present invention is applied, and which is the type referred to in the appended claims, is that comprising in combination a rotatable riser-wheel so carried that as the wound yarn-package attains a predetermined diameter, the wheel will, at the lower end of its traverse, engage the wound yarn, and mechanical means for rotating the riser-wheel comprising a ratchet-wheel rotatable together with the riser-wheel and a pawl mounted in an oscillating frame so that its nose can engage the teeth of the ratchet-wheel. The riser-wheel is preferably mounted on, and is in screw-threaded engagement with, a screw-threaded rod carried on the usual rising and falling bar; or, alternatively, it may be otherwise operatively engaged with the rod so that as it rotates it will travel lengthwise of the rod.

It will be understood that in this type of riser mechanism it is intended that the drive for the ratchet-wheel shall be such that the rate at which it will advance the riser-wheel lengthwise of the yarn-package will not of itself be sufficient to accommodate the rate at which the diameter of the yarn-package will increase, and in consequence reliance is placed upon the engagement of the edge of the riser-wheel with the surface of the yarn-package to rotate and advance the riser-wheel the amount required to make up for the deficiency in the advance imparted to it by the ratchet mechanism alone. The engagement of the riser-wheel with the yarn-package will only occur at one end of the reciprocating stroke of the riser-wheel, it being understood that the latter is continuously reciprocated relatively to the yarn-package in the lengthwise direction thereof in addition to the advance movement imparted to the riser-wheel along its supporting spindle.

In dealing with very fine yarns such as fine counts of artificial silk, spun silk or

the like, the operation of the riser mechanism has to be not only very certain in action but also light or delicate in its movement. An object of the invention is to improve riser mechanism of this type so that inertia and frictional resistance to movement of the riser-wheel on its spindle are brought within practical limits to enable a yarn-package to be produced having, when completed, an exterior surface that is smooth and uniform in appearance.

According to the present invention, riser mechanism of the above type has as one feature the combination of a rotatable riser-wheel, a ring of ratchet-teeth rotatable with the riser-wheel and an oscillatory pawl for engaging the teeth of the ratchet-wheel, said pawl being pivoted intermediate its two ends and sufficiently to one side of its center of gravity that it will be biased so that its nose is held in engagement with the ratchet-teeth by gravity alone. Preferably, the tail end of the pawl on one side of the pivot therefore will be biased to hold the nose in engagement with the ratchet-teeth. The bias can be, and conveniently is, made so light that a backstop pawl is unnecessary.

In one form of the invention, there is provided a let-off device comprising an arm that is mounted independently of the pawl, is normally held by the running yarn away from the pawl, but is so positioned that when released by the breakage or giving-out of the yarn, it will move into engagement with the tail end of the pawl and rock the latter on its pivot to disengage the nose from the ratchet-teeth. In one form, the let-off device is constituted by an arm pivotally mounted intermediate its two ends so that it is gravitationally biased to swing one end into engagement with the pawl, and at the other end the let-off arm constitutes a yarn-guide against which the yarn will drag with sufficient pressure to hold it against its gravitational bias.

The foregoing and other features of the invention will be more clearly understood from the following description of one preferred form of the invention described in

conjunction with the accompanying drawings, in which—

Figure 1 is a plan view of the riser mechanism, looking down from above;

5 Figure 2 is a partial elevation of the riser mechanism shown in Figure 1, and

Figure 3 is an elevation looking from the left of Figure 2.

Like reference numerals indicate like parts 10 in the several figures of the drawings.

The usual rising and falling bar is shown at 10 and extends in known manner along the front of the machine carrying any desired number of riser mechanisms similar 15 to that now to be described. The riser mechanism is carried on a bracket 11 bolted to the rising and falling part 10, and consists essentially of a screw-threaded riser-rod 12, a riser-wheel 13 rotatable on the rod 12 and 20 in screw-threaded engagement therewith, and a guide-rod 14 parallel with the rod 12. The rod 14 is secured at its lower end to the bracket 11 and is steadied at its upper end by means of a link 15 connecting it with the 25 upper end of the rod 12.

The means by which the wheel 13 is engaged with the threads of the rod 12 comprises a strip 16 which is mounted on an upstanding boss 17 constituting a part of 30 the wheel 13 by means of screws 18 which pass through slots in the strip 16. A ball 19 is normally pressed by a spring 20 against the underside of the strip 16. The latter is slotted where the shanks of the screws 18 35 pass through it so that it may have limited movement in the direction of a diameter of the wheel 13, and one edge of the aperture in the strip 16 which encircles the rod 12 is intended to engage the screwthread of the 40 rod. The ball 19, when the edge of the strip 16 is thus in engagement with the threads of the rod, presses into an indentation in the strip and so holds it in position. To disengage the edge of the strip from the 45 screwthread, the strip can be pressed to the right in Figure 2.

The strip or plate 16 is formed with an aperture through which the screwthreaded rod 12 passes and the aperture is slightly 50 larger in diameter than the rod. The plate in its operative position in which it is retained by the ball 19 will be such that the aperture is eccentric with respect to the axis of the rod 12 and one edge (the right-hand 55 edge in Figure 1) of the aperture in the strip or plate 16 will enter the screwthreads but this edge will not be pressed, as in hitherto known constructions, into engagement with the bottoms of the grooves of the screw- 60 thread, or at least not with any material degree of frictional engagement therewith. It will, however, engage with the sides of the screwthread to constitute the equivalent of a nut portion for the riser wheel 13. Ob- 65 viously, if the strip or plate 16 is pushed

to the right to bring its aperture into a position of concentricity with the axis of the rod 12 the engagement with the screwthread of the rod will be released and the riser wheel can then as a whole be slid lengthwise along 70 the rod 12.

Projecting downwardly from the wheel 13 is a tubular sleeve 21 which passes over the rod 12, and secured to rock on this sleeve is a boss 22 held in place between 75 an upper collar 23 and a lower collar 24 that is held in place on the sleeve 21 by means of set-screws 25.

From the collar 23 there is an arm 26 that, at its outer end, embraces and slides 80 on the rod 14. The boss 22 has also a radially-projecting arm 27, the outer end of which embraces and can slide on a rod 28 to be described more fully hereinafter. On a lateral projection from the boss 22 there 85 is mounted, by means of a screw 29, a rocking pawl 30, the nose of which is intended to engage a ratchet-wheel 31 which, in the present case, is cast integral with and on the underside of the wheel 13. This is the 90 gravity-actuated pawl hereinbefore mentioned, the tail of which is normally sufficiently biassed so that the nose is held by gravity in engagement with the teeth of the wheel 31. On the arm 27 is mounted, by 95 means of a screw 32, a pivoted lever constituted by a central block 33 and wires 34 and 35 extending outwardly from both sides of the block. The end of the wire 35 is turned so as to lie underneath the tail of 100 the pawl 30, whereas the wire 34 is also bent round at its outer end and at 36 constitutes a guide under which the yarn is led from the hank or spool from which it is to be wound, and thence through a yarn-guiding eye 37, which itself is carried at the end of another wire projecting from the arm 27. From the eye 37 the yarn passes to the spool 38 on which the yarn is being 105 wound.

From a fixed front rail 39 of the machine there projects beneath the riser mechanism a rod 40 that is rotatable about its longitudinal axis and carries an upwardly-projecting rod 41, the angle of which, in relation 115 to the axis of the rod 12, can be adjusted by rotation of the rod 40 about its axis. A pointer 42, rotating with the rod 40, can be set in conjunction with the scale 43 carried on the fixed rail 39.

Engaging the rod 41 is an eye situated at the end of a radial arm 44, which is also mounted to rock on the screwthreaded rod 12 below the bracket 11. The arm 44 is held in place by means of a collar 45 clamped to the rod 12 by means of set-screws such as 46. The rod 28 is mounted on the arm 44, and in order that, as the mechanism is moved up and down by the rising and falling rail 10, the eye at the end of the arm 130

44 may travel up and down the inclined rod 41, the eye is provided at the end of a short slider 47 carried in bearings 48 on the arm 44.

5 In operation, the action of the apparatus is as follows:—The yarn is led to the spool 38 under the yarn-guide 36 so that the end 35 of the pivoted yarn-guide is held free of the tail end of the pawl 30. The nose of the pawl is, therefore, held by gravity in engagement with the ratchet-teeth 31, as shown in Figure 2. As the rising and falling rail 10 carries the parts up and down, the rod 28 will be moved backwards and 10 forwards angularly about the axis of the rod 12, and, in so doing, will rock the boss 22 and with it the pawl. The amount of 15 angular rotation thus imparted to the wheel 13 will depend upon the angle at which the bar 41 is set in relation to the axis of the rod 12, and this will generally be such that the mechanical feed imparted to the wheel 13 is insufficient by itself to rotate the wheel 20 sufficiently to feed it along the rod 12 at the required rate. When the wound yarn-package attains the requisite diameter, the wheel 13, in known manner, will frictionally 25 engage with the yarn and will be given an added rotation by this engagement, and, in so doing, the ratchet-teeth 31 will ride over 30 the pawl 30. The latter is, however, so designed that its gravitational bias is very light, and the friction imposed on the movement of the wheel due to the engagement 35 of the pawl with the ratchet-teeth, is so slight as to be almost negligible.

It is also so light that no back-stop pawl is required, and, consequently, the friction 40 of the pawl against the ratchet-wheel is very much less than would be that of the two pawls, for example, of the apparatus described in the specification of British Letters Patent No. 227,013.

45 If the yarn fails or breaks, the guide 36 will no longer be supported by the yarn and as the natural bias of the rocking arm 35, 32, 34, 36 is such as to allow the end 36 to drop, the yarn will swing about its pivot to bring the end 35 beneath the tail end of 50 the pawl 30 and thereby disengage the nose of the pawl from the ratchet teeth 31. The weight of the extremity 34, 36, is such that the swinging arm as a whole is gravitationally biased, when freed from the yarn, to 55 bring the end 35 into engagement with the pawl for the purpose just described.

The wheel 13 and its boss 17 may be made 60 of aluminium or other light metal so that the inertia of the wheel is as small as possible.

65 The riser mechanism according to this invention is found to work with great accuracy with the very lightest of silk or artificial silk yarns, and will work with equal or even

greater accuracy with heavier classes of yarn.

I claim:—

1. Riser-mechanism of the kind described comprising in combination a rotatable riser-wheel, a ring of ratchet-teeth rotatable with the riser-wheel, an oscillatory pawl for engaging the teeth of the ratchet-wheel and normally held by gravity alone in engagement with the ratchet-teeth, and a let-off device comprising an arm that is pivotally mounted independently of the pawl, is normally held by the running yarn away from the pawl and is so positioned that, when released by breakage or failure of the yarn, it will move into engagement with the pawl and will rock the latter on its pivot to disengage the pawl from the ratchet-teeth. 70

2. Riser-mechanism of the kind described comprising in combination a rotatable riser-wheel, a ring of ratchet-teeth rotatable with the riser-wheel, an oscillatory pawl for engaging the teeth of the ratchet-wheel, said pawl being pivoted intermediate its two ends and sufficient to one side of its centre of 75 gravity that its tail end will be biassed to hold the nose in engagement with the ratchet-teeth by gravity alone, and a let-off device comprising an arm that is mounted independently of the pawl, is normally held by the running yarn away from the pawl, and is so positioned that, when released by breakage or failure of the yarn, it will move 80 into engagement with the tail end of the pawl and rock the latter on its pivot to disengage the nose of the pawl from the ratchet-teeth. 85

3. Riser-mechanism of the kind described comprising in combination a riser-wheel, a ring of ratchet-teeth rotatable with the riser-wheel, an oscillatory pawl for engaging the teeth of the ratchet-wheel and normally held by gravity alone in engagement with the ratchet-teeth, and a let-off device comprising an arm which is pivotally mounted intermediate its two ends independently of the pawl, which at one end constitutes a 90 yarn-guide against which the running yarn will bear with sufficient pressure to hold it away from the pawl, and which is gravitationally biassed so that on breakage or failure of the yarn, it will swing the other end into engagement with the pawl to disengage it from the teeth of the ratchet-wheel. 95

4. Riser-mechanism of the kind described comprising in combination a rotatable riser-wheel, a ring of ratchet-teeth rotatable with the riser-wheel, an oscillatory pawl which is pivoted intermediate its two ends sufficiently to one side of its centre of gravity so that its tail end will be biassed by gravity 100 alone to hold the nose against the ratchet-teeth, and a let-off device comprising an arm which is mounted independently of the 105

110

115

120

125

130

- 5 pawl, which at one end constitutes a yarn-guide against which the running yarn will bear with sufficient pressure to hold it against its bias away from the ratchet-teeth, and which, when released by breakage or failure of the yarn, will swing by gravity to bring its other end into engagement with the tail of the pawl so as to disengage the latter from the ratchet-teeth.
- 10 6. Riser-mechanism of the kind described comprising in combination a rotatable riser-wheel, a screw-threaded rod on which the riser-wheel is mounted, an aperture in the riser-wheel through which the rod passes and which is large enough to slide freely on the rod, and an endwise-movable strip mounted on the riser-wheel and formed with an aperture through which the rod passes and which is larger in diameter than that of the rod, means to hold the plate on to the riser-wheel but to permit endwise movement of the plate to enable an edge of the aperture in it to be engaged with the screw-thread of the rod, and holding means normally to retain the plate in the position in which it is engaged with the screw-thread.
- 15 7. Riser-mechanism of the kind described comprising in combination a screw-threaded rod, a riser-wheel mounted thereon, a ring of ratchet-teeth formed integrally with the under surface of the riser-wheel, a pawl arranged to oscillate about the axis of the riser-wheel and pivoted intermediate its two ends sufficient to one side of its centre of gravity so that its tail end will be biassed to hold its nose against the ratchet-teeth, the gravitational bias of the pawl being so light that a back-stop pawl is unnecessary, an endwise-movable strip mounted on the riser-wheel and having an aperture through which the rod passes and of larger diameter than that of the rod, means to hold the strip on to the riser-wheel but to permit of endwise movement of the strip to enable an edge of the aperture therein to be engaged with the screw-thread of the rod, holding means normally to retain the plate in the position in which it is engaged with the screw-thread, and a let-off device which is mounted independently of the pawl, which is pivotally mounted intermediate its two ends, which is gravitationally biassed to swing one end into engagement with the tail of the pawl, and which, at the other end, constitutes a yarn-guide against which the running yarn will bear with sufficient pressure to hold it against its bias away from the pawl.
- 20 8. Riser mechanism comprising in combination a rotatable riser-wheel formed to engage with the surface of a yarn-package, a ring of ratchet teeth rotatable with the riser-wheel, an oscillatory pawl for engaging the teeth of the ratchet-wheel, said pawl being pivoted intermediate its two ends and sufficiently to one side of its center of gravity that it will be biassed to hold the nose of the pawl in engagement with the ratchet-teeth by gravity alone, and pawl-actuating means to drive the ratchet-wheel at a rate less than that necessary by itself to form the wound yarn package.
- 25 9. Riser mechanism comprising in combination a rotatable riser-wheel formed to engage with the surface of a yarn-package, a ring of ratchet-teeth rotatable with the riser-wheel, an oscillatory pawl for engaging the teeth of the ratchet-wheel, said pawl being pivoted intermediate its two ends and sufficiently to one side of its center of gravity that its tail end will be biassed to hold the nose of the pawl in engagement with the ratchet-teeth by gravity alone, and pawl-actuating means to drive the ratchet-wheel at a rate less than that necessary by itself to form the wound yarn-package.
- 30 10. Riser mechanism comprising in combination a rotatable riser-wheel formed to engage with the surface of a yarn-package, a ring of ratchet teeth rotatable with the riser-wheel, an oscillatory pawl for engaging the teeth of the ratchet-wheel, said pawl being pivoted intermediate its two ends and sufficiently to one side of its center of gravity that it will be biassed to hold the nose of the pawl in engagement with the ratchet-teeth by gravity alone, and pawl-actuating means to drive the ratchet-wheel at a rate less than that necessary by itself to form the wound yarn-package, the gravitational bias of the pawl being so light that a backstop pawl is rendered unnecessary.
